DESIGN FOR A SIGNAL REFLECTOR FOR VEHICLES

Raymond H. Osbrink, Los Angeles, Calif.

Application December 4, 1935, Serial No. 59,902

Term of patent 3½ years

To all whom it may concern:

Be it known that I, Raymond H. Osbrink, a citizen of the United States and residing at Los Angeles, in the county of Los Angeles and State of California, have invented a new, original, and ornamental Design for a Signal Reflector for Vehicles, of which the following is a specification, reference being had to the accompanying drawing, forming a part thereof.

In the accompanying drawing, Fig. 1 is a front elevation, of the signal reflector for vehicles, showing my new design;

Fig. 2 is a top plan view; and

Fig. 3 is an end view.

I claim:

The ornamental design for a signal reflector for vehicles, substantially as shown.

RAYMOND H. OSBRINK.
